UNITED STATES PATENT OFFICE.

JOSEPH W. BOWEN, OF PHILADELPHIA, PENNSYLVANIA.

DESIGN FOR A LAST.

SPECIFICATION forming part of Design No. 29,161, dated August 2, 1898.

Application filed July 5, 1898. Serial No. 685,174. Term of patent 14 years.

To all whom it may concern:

Be it known that I, JOSEPH W. BOWEN, a citizen of the United States, residing in Philadelphia, Pennsylvania, have invented a new and original Design for a Last for Boots or Shoes, of which the following is a specification.

My design is fully shown in the accompanying drawings, in which—

Figure 1 is an inverted perspective view of the last. Fig. 2 is a side view of the same, and Fig. 3 is a rear view.

The main feature of the design is a projection extending downward from the under side of the heel of the last and following the general outline of the heel portion of the last, but of less dimensions than the same, so as to form a shoulder around the projection at the sides and rear of the heel.

In the drawings, 1 represents the heel projection, and 2 the shoulder, extending around the same at the sides and rear of the heel.

Having thus described my invention, I claim and desire to secure by Letters Patent—

The design for a last for boots or shoes, substantially as described and as shown in the accompanying drawings.

In testimony whereof I have signed my name to this specification in the presence of two subscribing witnesses.

JOSEPH W. BOWEN.
